UNITED STATES PATENT OFFICE.

JULIUS PINTSCH, OF BERLIN, PRUSSIA, GERMANY.

APPARATUS FOR HEATING RAILWAY-CARS WITH GAS.

SPECIFICATION forming part of Letters Patent No. 336,585, dated February 23, 1886.

Application filed September 11, 1884. Serial No. 142,783. (No model.) Patented in Belgium September 8, 1884, No. 66,254; in France September 8, 1884, No. 164,176; in England September 8, 1884, No. 12,140, and in Austria-Hungary March 23, 1885, No. 34,133 and No. 15,875.

To all whom it may concern:

Be it known that I, JULIUS PINTSCH, engineer, of the firm of Julius Pintsch, at Berlin, O., a subject of the King of Prussia, residing at Berlin, O., 72 and 73 Andreas Strasse, German Empire, have invented certain new and useful Improvements in Apparatus for Heating Railway-Cars with Gas; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to that class of heaters for railroad-cars which are located outside thereof, and known as "pendent heaters," wherein air is heated and admitted to the car.

The object of this invention is to increase the efficiency of this class of heaters and simplify their construction; and it consists in the construction, arrangement, and combination 25 of the elements or parts which constitute the heater, substantially as hereinafter fully described, and as shown in the accompanying drawings, in which—

Figure 1 is a longitudinal vertical section 30 of so much of a railroad-car as is necessary to illustrate my invention. Fig. 2 is a vertical transverse section of the same. Fig. 3 is a sectional longitudinal elevation; Fig. 4, a sectional plan view, and Fig. 5 a sectional end 35 view, of the heating apparatus. Fig. 6 is an elevation, and Fig. 7 a vertical section; Fig. 8, a top plan view; and Fig. 9, a horizontal section on line $x-x$ of Fig. 7, illustrating my improved burner.

Like letters of reference indicate like parts wherever such may occur in above figures of drawings.

The heating apparatus is contained in a box, A, secured to the under side of the car at any convenient point, preferably as near the longitudinal center thereof as possible, and near one or the other side. To prevent radiation and consequent loss of heat, the box may be covered or lined with any suitable non-con-

ductor of heat, such as felt, asbestos, or other 50 suitable material. It will be found that inclosing the box or casing B in a wooden box will answer all the purposes.

The described means for preventing loss of heat by radiation are well known, and form 55 no part of this invention. I have therefore deemed it unnecessary to illustrate the same in the drawings.

The air-heating apparatus consists of heat-radiating elements composed of ribbed pipes 60 P, through which pass the heated air and gases and the products of combustion from the burners B. Any desired number of these radiators P may be employed according to the amount of heat required, and also according 65 to the space afforded below the car.

At the point where the heated gases enter the radiators P the latter are provided with funnel-shaped inlet-pipes p, Figs. 3 and 5, the enlarged orifice of which is immediately above 70 the burners B. The gases and products of combustion, after passing through the ribbed pipes P, escape therefrom through a pipe, P', that is preferably extended to or above the roof of the car. The box A has a lateral 75 chamber, C, to which the cold air is admitted through a double funnel-pipe, c, in which is arranged in the well-known manner a valve or vane that will set itself invariably, according to the direction of motion of the car, to the 80 current of air, so as to admit air into the chamber C in whatever direction the train may be going. The partition-wall a of box A and chamber C is provided with numerous perforations, so as to subdivide the air admitted into 85 chamber C before it reaches the heating apparatus in box A.

The burner or burners B are arranged in a chamber, C', formed below box A, the bottom a' of which box has openings for the passage of the connecting-pipes p, that admit the heated gases and the products of combustion to the radiators P.

Above the bottom a' of box A is a chamber, C', formed by a reticulated or perforated 90 diaphragm, D, said chamber C' being in direct connection with the chamber C through the perforated partition-wall a of box A, as shown

- in Figs. 3 and 5. This perforated diaphragm serves to still further subdivide the air being heated, and in practice I preferably employ a diaphragm, D, having its perforations so arranged that one or more of said perforations d will lie immediately below and between the ribs P' of the radiators P on opposite sides thereof, as shown in Fig. 4. By means of this arrangement the air to be heated is compelled to pass over the heated surfaces of the pipe itself as well as over the entire surfaces of the heated ribs. I have found that by this mode of conducting the cold air over the heating-surfaces but an inappreciable amount of heat is lost, and this is of the greatest importance in a heating apparatus for railway-cars, for the reason that the space available for the application of the air-heating devices is usually very limited.
- Any suitable combustible may be employed for heating the air admitted from chamber C to chamber C' . I prefer to use a gas of such nature as to be capable of being stored under pressure and admitted to the burners with sufficient atmospheric air to produce a combustible gaseous mixture.

As above stated, the burner or burners are located in a chamber, C' , isolated from the interior of box A and from chamber C by the bottom a' of box A, and any suitable gas-burner may be employed. The chamber C' has one or more openings in which is secured a hooded air-inlet pipe, E, the discharge-opening e of which is provided with a deflecting-plate, c^2 , secured to the side wall of chamber C' , and extending in proximity to the opening e , down nearly to the bottom of the chamber, as shown in Fig. 3. This deflecting plate c^2 serves to regulate the admission of the air to the burners, B, to distribute the air throughout the chamber, and to prevent sudden puffs of air either to extinguish or otherwise affect the flame of the burners.

Any suitable gas-burner may be employed to heat the radiators P . It is, however, desirable that the combustion of the gas should be as complete as possible, to avoid any loss of heat, and to this end I prefer to employ the improved form of burner shown in Figs. 6 to 9. The burner B consists of a tubular body, b , having walls of comparative great thickness, and flaring inlet and outlet orifices b' b^2 , respectively, as shown in Fig. 7. Below the lower or inlet orifice, b' , is formed a chamber, B' , having a number of air-inlet ports or orifices, b^3 . The outer end of said chamber is screw-threaded to receive the correspondingly-threaded portion g of the gas-pipe G, the top of which extends nearly to and centrally of the flaring inlet-orifice of the body b of the burner. The pipe G has an annular flange or collar, g' , that lies against the annular face of the chamber B' of burner B, and closes said chamber at its lower end, said pipe being further provided with a seat flange or collar, g^2 , for securing the same to the bottom of chamber C' of the heating apparatus. This

latter collar or flange may, however, be dispensed with and the collar or flange g' may serve as a seat-flange. I prefer, however, to slightly elevate the chamber B' above the floor of the chamber C' , to insure a better circulation of the air from the inlet-pipe c^2 to the air-chamber B' of the burner. To the upper end of the body of the burner is seated a deflecting cap or disk, F, that is provided with depending legs or wings f , adapted to rest upon an offset or annular shoulder, b^4 , formed at the upper end of the body b of the burner. The length of these legs or wings f relatively to the distance between the offset b^4 and the mouth of the burner is such that when the deflecting-disk is in proper position on the burner-body there will be found between the lower face of the disk and the upper face of the body b of the burner a narrow annular slit or opening, f' , for the passage of the gas. In order to better distribute the jet of gas to and around said opening f' , the disk F is provided with a depending deflecting-cone, F', extending into the flaring mouth b^2 of the burner b , as shown in Fig. 7. It will be observed that by constructing the walls of the body of the burner so as to flare outwardly at the discharge-orifice b^2 , as described, and by providing the deflecting-disk F with a deflecting-cone, F', flaring inwardly or in a reverse direction on practically diverging lines I not only obtain a perfect and uniform distribution of the jet of gas to the annular burner-slit f' , but I also obtain a tapering discharge orifice or slit that is narrowest at the point where the gas issues between the disk F, and the upper face of the burner-body, and thence gradually widens inwardly, as plainly shown in said Fig. 7. The air-chamber B' of the burner is surrounded by a sheet-metal diaphragm or short cylinder, H, made to flare outwardly at its upper open end, h , said cylinder being secured to the flange or collar g' of the gas-pipe G.

To the body b of the burner is secured a cap, I, extending outwardly and over the inclosing diaphragm or cylinder H, and surrounding the same at its upper flaring mouth, at which point said cap has an annular opening, i , for the passage of the air admitted to chamber B' . The object of this arrangement is to provide a circuitous path for the air before it is admitted to the chamber B' of the burner, to commingle with the gas, whereby said air is first thoroughly heated.

The body b and disk F of the burner are made of metal, and the cylinder H and cap I of sheet metal. After the jet of gas has been ignited these parts become very much heated and heat the air admitted to chamber C' prior to its reaching the chamber B' of the burner, thereby insuring not only a good draft, but an almost perfect combustion of the gas. The surplus of air, if any, not needed for combustion passes through the radiators P and serves to heat the same.

The air admitted to chamber C' and thence to the interior of the heater-box A, after

passing over the heating-surfaces of the radiators P, as above described, passes out of the box A in a heated condition by a pipe, k, connected with a distributing main or mains, 5 K, that extend along the car from opposite sides of the heating apparatus, and said main or mains connecting with branches k', that extend under the seats of the car at suitable or convenient distances apart.

10 In practice I employ perforated branches k' to distribute the hot air under the seats of the car, in close proximity to the floor, as shown in Fig. 2, and by preference I form the perforations on the under side of the pipe to force 15 the hot air downward toward the floor. This, however, is not necessary, nor is it absolutely necessary to use perforated hot-air branches k', as it is obvious that radiators may be employed, or registers at any suitable point in 20 the floor of the car.

To regulate the volume of hot air admitted when perforated or open distributing pipes are used, I arrange a valve in the exit-pipe K of the heating apparatus, adapted to be controlled 25 either from within or from without the car, as may be found most convenient. When the hot air is admitted through registers, the latter are provided with the usual means for regulating the volume of hot air passing 30 through the same.

The gas under pressure may be stored in a suitable reservoir, R, located below the car, in proximity to the heating apparatus; or said reservoir may be located at any other suitable 35 or convenient point within or without the car, so as to admit of its being readily replenished with gas under pressure, or taken off when exhausted and a charged reservoir substituted therefor. The reservoir should be located at 40 some point of the car from which the supply of gas to the burners may be regulated, and for this purpose said reservoir may be located on the tender of the locomotive or in the baggage or mail car, and placed under the supervision of some officer of the train, the connection 45 with the various heating apparatus being effected by flexible couplings in a manner similar to the coupling of the air-pipes in the Westinghouse air-brakes, or in any other convenient or desirable manner.

When a reservoir common to all heating apparatuses is placed under the control of an officer of the train, the supply of gas to the burners, and consequently the degree of heat 55 in the cars, may be regulated by regulating the supply of gas to the heating apparatuses.

The described arrangement of reservoir and connections therefor are merely given as an illustration of the manner in which the gas 60 may be distributed to the heaters; but of course any other arrangement may be adopted, and as I do not desire to claim any particular arrangement of distribution or any particular device for controlling the supply of gas to the heaters, I have deemed it unnecessary to illustrate 65 the same.

It is obvious that in case of derailment or a

collision the connection between the different heaters and their reservoir would be interrupted, the flow of gas would therefore cease 70 and the burners be extinguished, the communication between the gas-reservoir and the heating apparatuses in case of accident may be instantly cut off by the officer in charge.

I do not desire to confine myself to the use 75 of the described radiators P or the burners B, as it is evident that radiators and burners of other suitable construction and form may be employed, though I believe that a very material saving of heat is effected by the use of 80 the said radiators P and burners B; nor do I desire to confine myself to any particular arrangement of devices for distributing the heat throughout the cars, or to providing a gas-reservoir for each heating apparatus, or 85 to the connecting of the same to a common reservoir, although I prefer the latter, as the most convenient and economical.

Any other suitable means than those specified 90 may be employed for regulating the volume of hot air admitted to a car—as, for instance, instead of controlling or regulating the supply of gas or the extent of the interior passage of the exit-pipe by a valve, the distributing-pipes may each be provided with a controlling-valve, and instead of employing perforated piping a perforated case or box may be employed for distributing within the cars of the hot air from the heaters.

Having now particularly described my said 100 invention, what I claim as new, and desire to secure by Letters Patent, is—

1. In a heater for railroad-cars, the combination, substantially as herein described, of a hot-air chamber in communication with the 105 interior of the car, a chamber, C², communicating with the outer air, and a burner arranged in said chamber C², with a tubular heat-radiator arranged in said hot-air chamber, one end of which radiator communicates 110 with chamber C² by a funnel-pipe, p, located above the burner, and the other with the outer atmosphere, and a cold air-admission chamber communicating with the hot-air chamber through a perforated partition-wall, for the 115 purposes specified.

2. In a heater for railroad-cars, the combination, with an inclosing-casing in communication with the car, and a tubular heat-radiator provided with radiating ribs or flanges P' 120 arranged therein, of a cold-air chamber and a perforated air-distributing diaphragm interposed between the radiator and cold-air chamber, having its perforations arranged to register with the spaces between the said ribs 125 P' of the radiator, substantially as and for the purpose specified.

3. In a heater for railroad-cars, the combination, with an inclosing-casing and a heat-radiator arranged therein provided with radiating-ribs P, of a diaphragm provided with perforate and imperforate portions arranged below the radiator, the perforate portions thereof registering with the spaces between 130

the ribs of the radiator, said diaphragm dividing said casing into air-heating and cold-air chambers, respectively, substantially as and for the purpose specified.

- 5 4. In a heating apparatus for railroad-cars, the combination, substantially as herein described, with an inclosing case or box in communication with the car, a ribbed tubular air-radiator, P P', arranged in said casing and 10 communicating at one end with the outer atmosphere, a perforated diaphragm interposed between the radiator and one of the walls of the casing, and having its perforations arranged to register with the spaces intermediate 15 of the ribs P' of the said radiator, and a cold-air chamber communicating with the space between the diaphragm and wall of the casing through a perforated partition, of a burner-chamber and burner in communication with 20 the tubular heat-radiator and the atmosphere, for the purpose specified.

5. The combination, substantially as herein described, with the casing A, having a portion of its wall a perforated, the perforated 25 diaphragm D, dividing the casing into two chambers, the heat-radiator P, arranged in one of said chambers, and the chamber C, com-

municating, through the perforations of wall a, with the other chamber, of a burner-chamber and burner communicating with the radiator through funnel pipe p, said parts being constructed and arranged for operation for the purpose specified. 30

6. In a heater for railroad-cars, the combination, with an inclosing-casing and a heat-radiator provided with radiating-ribs P' arranged therein, of a diaphragm having perforate and imperforate portions arranged below the radiator, the perforate portions thereof registering with the spaces between the ribs 40 of the radiator, said diaphragm dividing the casing into air-heating and cold-air chambers, respectively, and a cold-air-admission chamber in communication with the cold-air chamber of the casing through a perforated partition, substantially as and for the purpose specified. 45

In testimony whereof I affix my signature in presence of two witnesses.

JULIUS PINTSCH.

Witnesses:
